UNITED STATES PATENT OFFICE.

JAMES YOUNG, OF KENTON, OHIO.

IRON GATE.

SPECIFICATION forming part of Letters Patent No. 235,113, dated December 7, 1880.

Application filed May 29, 1879.

To all whom it may concern:

Be it known that I, JAMES YOUNG, of Kenton, in the county of Hardin and State of Ohio, have invented certain new and useful Improvements in Iron Gates; and I do hereby declare the following to be a full, clear, and exact description of the invention, such as will enable others skilled in the art to which it pertains to make and use it, reference being had to the accompanying drawings, which form part of this specification.

My invention relates more particularly to the hinges on iron gates; and it consists, first, in constructing the hinge in such a manner that it shall serve the double purpose of a hinge and a coupling for the adjacent parts of the gate, whereby those parts of the gate are fastened together; second, in forming the hinge-piece in two parts, each part so fashioned that when clamped together upon the adjacent parts of the gate they will fasten those parts together, and either one or both of said parts being provided with a passage-way for the hinge-rod; third, in providing a hinge-rod with a bent top, so that while the body of the rod is straight and parallel with the fence-uprights the top by being bent will form a short hinge, thereby causing the gate to close automatically by gravitation.

In the drawings, Figure 1 is a representation of a gate, showing my hinge applied. Fig. 2 is a perspective view of the hinge parts, such as constitute the top hinge shown. Fig. 3 is a perspective view of the parts constituting the lower hinge, being a variation of the construction shown in Fig. 2, but embodying the same principles.

In the said drawings, A represents the gate, and B the adjacent section of the fence. A' represents the upright of the gate that is adjacent to the hinge. A² represents the horizontal portions of the gate-frame. C is the hinge-rod. D and D' are the parts which constitute the top hinge; E E', the parts which constitute the lower hinge.

Frequently iron gates are made with the upright A' in the form of a rod, bar, or pipe, and the parts A² of a similar nature. I propose, therefore, to make a hinge-piece which shall at the same time serve to form one of the

joints whereby the parts A' and A² are fastened together at their junction. To this end I form a hinge in two parts, D and D'. To one part, D, I provide a suitable bracket-arm, d, and eye D², for the passage of the hinge-rod, 55 and in so forming the hinge I prefer to cast the eye D² around a core. The piece D is also provided with a partial seat for the upright A' and the cross-piece A². The other part, D', of the hinge is made to fit upon the part D, 60 and is likewise provided with partial sockets or seats for the upright and cross-piece, so that when put together they will snugly grasp the said upright and cross-piece. Corresponding bolt-holes through the upright, the cross-piece, 65 and the parts D and D' of the hinge enable the structure to be securely bound together by bolts or rivets.

It is not essential that the part D should be cast with the whole of the eye D², for it is apparent that, as shown in Fig. 3, the eye may be separated in the casting, so as to be formed by bringing the two castings together, as shown, and I do not limit myself to either particular construction. So, also, instead of having rounded passage-ways for the parts A' and A² of the gate, it is apparent that these passage-ways or seats may be fashioned to suit any form of section which may be employed in the construction of the gate.

The drawings represent the top gate-hinge made in accordance with the device shown in Fig. 2 and the bottom hinge in accordance with the variations shown in Fig. 3; but either one may be employed in either locality.

The lower hinge has a longer bracket-arm than the upper hinge, so that the gate, when opened, shall shut by gravitation.

The hinge-rod C is made straight, so as to stand parallel with the fence-uprights from 90 bottom to top, its top is then bent over upon itself, so as to pass through the eye of the upper hinge and compensate for the different lengths of the bracket-arms of the upper and lower hinges.

What I claim is—

1. A gate-hinge made in two parts, provided with half-sockets, whereby, when fastened together, they will embrace between them the adjacent part of the gate, and at the same 100

time form an eye for the passage of the hinge-rod, substantially as and for the purposes described.

2. A gate-hinge made in two parts, provided with half-sockets adapted to embrace and unite the adjacent upright and cross-piece of the gate, and at the same time form an eye for the passage of the hinge-rod, substantially as and for the purposes described.

10 3. The combination, with a gate, gate-post, and hinges, of a hinge-rod having one extremity provided with a portion formed in a return-bend, and said extremity fitting in eyes formed respectively in both parts of a hinge, substantially as set forth.

4. The combination, with a gate, gate-post, and hinges, of a hinge-rod having one extremity provided with a portion formed in a return-bend, and said extremity fitting in eyes formed respectively in both parts of a hinge, the main body of the rod passing through a socket formed in one part of said hinge, substantially as set forth.

5. The combination, with a gate, gate-post, and hinges, of a hinge-rod whose lower extremity passes through eyes formed respectively in both parts of the lower hinge, and whose upper extremity passes through a socket formed in one of the two parts of the upper hinge, said upper extremity being provided with a downwardly-bent portion, which fits in eyes formed in both parts of the upper hinge, substantially as set forth.

6. A hinge for iron gates, cast in two parts, each part forming the half of a vertical and a horizontal socket, said halves constructed to form when united a projecting arm with an eye in the outer end thereof, substantially as set forth.

In testimony whereof I have signed my name to this specification in the presence of two subscribing witnesses.

JAMES YOUNG.
